(57) **CLAIM**

The ornamental design for a buffer tube mount, as shown and described.

DESCRIPTION

FIG. 1 is a top perspective view of a buffer tube mount;
 FIG. 2 is a left side elevation view thereof;
 FIG. 3 is a right side elevation view thereof;
 FIG. 4 is a rear elevation view thereof;
 FIG. 5 is a front elevation view thereof;
 FIG. 6 is a top plan view thereof; and,
 FIG. 7 is a bottom plan view thereof.

The broken lines depict portions of the article that form no part of the claimed design.
